COMBINED HANDLE AND IDENTIFICATION TAG FOR A WALKING CANE

Augustine Y. Murillo, 127 S. Boyle Ave.,
Los Angeles, Calif. 90033

Filed July 21, 1966, Ser. No. 3,161

Term of patent 14 years

(Cl. D88—4)

FIG. 1 is a perspective view of a combined handle and identification tag for a walking cane, showing my new design;

FIG. 2 is a cross section taken along line 2—2 of FIG. 1.

The side opposite that shown in FIG. 1 is the same. The broken line showing a portion of a cane in FIG. 1 is for illustrative purposes only.

I claim:

The ornamental design for a combined handle and identification tag for a walking cane, substantially as shown and described.
